UNITED STATES PATENT OFFICE.

EDWARD G. SHORTT, OF CARTHAGE, ASSIGNOR OF ONE-HALF TO CHARLES G. EMERY, OF BROOKLYN, NEW YORK.

STEAM-ENGINE.

SPECIFICATION forming part of Letters Patent No. 437,460, dated September 30, 1890.

Application filed December 12, 1889. Serial No. 333,478. (No model.)

To all whom it may concern:

Be it known that I, EDWARD G. SHORTT, a citizen of the United States, residing at Carthage, in the county of Jefferson and State of New York, have invented new and useful Improvements in Steam-Engines, of which the following is a specification.

My present invention relates to that class of steam-engines having rocking valves of the type shown in United States Letters Patent No. 389,769, granted to me the 18th day of September, 1888.

It is the purpose of my invention to provide a simple form of cylindrical reversing-valve, adapted to seat upon the concave face of the rocking valve of engines of this type, the reversing valve having alternating, duplex, live steam, and exhaust ports, and being seated upon the concave face of the rocking valve, and being adapted to reverse the engine by a revolution upon its own axis of one hundred and eighty degrees, or to cut the steam entirely off by a revolution of ninety degrees.

The present invention is an improvement upon the invention covered by the Letters Patent recited above, and also upon the Letters patent granted to me the 18th day of September, 1888, No. 389,770; and it consists in the several novel features of construction and new combinations of parts hereinafter fully set forth and then definitely pointed out in the claims following this specification.

Referring to the accompanying drawings, Figure 1 is a horizontal section upon a plane passing centrally through the valve. Fig. 2 is a cross-section of the rocking and reversing-valve, taken upon the line xx , Fig. 1. Fig. 3 is a similar section of the same parts upon the line yy , Fig. 1, showing the valve in position to cut off the steam. Fig. 4 is a view in elevation of the reversing-valve. Fig. 5 is a similar view of the same reversed. Fig. 6 is a sectional elevation of the inner concave face, and Fig. 7 is a view of the outer rearward face of the rocking valve.

In the said drawings, the reference-number 1 denotes the duplex cylinders of the steam-engine, each having an independent

piston 2. The steam-chest 3 is upon the front of the cylinder-casing, and is provided with 50 a concave valve-seat 4, having ports 5, communicating with steam-passages 6, leading to the tops of the cylinders, and having ports 7 communicating with steam-passages 8, leading to the bottoms of said cylinders. The numeral 9 denotes the exhaust-openings, 55 communicating with passages 10 through the pistons and through the exhaust-pipe 12 in the rear. In all these respects the invention is not materially different from the inventions 60 contained in my said patents referred to above.

Arranged in the concave valve-seats 4 are oscillating valves 13, having each a stem 14 connected to the piston and lying in the exhaust-opening 9. This valve is provided with live-steam ports 15, which alternate with each other on opposite sides of transverse duplex exhaust-openings 16, and having exhaust-ports 17 alternating in like manner, and each 70 communicating with one of the parallel transverse exhaust-openings 16. The bodies of these valves are substantially cylindrical in form, and each one is provided with a true cylindrical opening fitting steam-tight upon 75 the reversing-valve, as hereinafter shown. The seating portion of each valve is designated by the numeral 18, and it contains the live-steam and exhaust ports already described. This seating portion comprises one 80 hundred and eighty degrees (more or less) of the entire cylindrical body, and the remaining portion of each consists of the shell 19, which is cut away upon its outer face, as shown in Figs. 2 and 3, thereby forming, when the valve 85 is arranged upon its seat, a semi-annular chamber 20 within the steam-chest. In each valve ports 21 and 22 are cut through the semi-cylindrical shell 19, each port being diametrically opposite the septum which separates the live-steam and exhaust ports from each other upon each side of the valve-stem. These rocking or oscillating valves inclose a cylindrical valve 23, having journals 24 at its ends, which journals have bearing in the end 90 walls of the steam-chest. This valve is co-

extensive in length with the rocking valves 13, and is provided with live-steam ports 25 and 25^a, cut entirely through the cylindrical body at right angles to its axis, said steam-ports 5 being arranged alternately upon opposite sides of transverse lines coinciding with the exhaust-openings 16 of the rocking valve 13—that is to say, one port being above the axis of the valve and the other live-steam port on 10 the opposite side of or below the valve-axis upon the other side of the stem.

In the body of the cylindrical valve are formed Z-shaped exhaust-channels 26, the horizontal parts thereof being cut in nearly 15 to the axial plane and alternating with the live-steam ports, as shown. These channels communicate with a transverse channel 27, common to both exhaust-channels and forming the upright or connecting part of the Z, 20 and similar channels are cut upon the opposite side of the cylindrical body, as shown in Fig. 2, the two being separated by a web 28 of metal. The reversing-valve has four live-steam ports or four of the exhaust-channels 25, two of the latter upon each side of the cylinder. It will be readily seen that by turning 30 the valve through half of a revolution the relative positions of the live-steam ports will be reversed, as in Figs. 4 and 5, while a similar reversal of the exhaust-channels 26 is simultaneously effected. This cylindrical valve being placed within the rocking or oscillating cylindrical valves 13, as described, 35 may be turned upon its axis by means of a lever or crank arm 29, mounted upon a prolongation 30 of one of the journals of the valve, the latter passing through a stuffing-box 31. In this position it may be so placed that the rocking or oscillating valves 13 will 40 supply live steam to and exhaust from the cylinders in a manner clearly evident from the drawings and description. By rotating the valve 23 through an arc of ninety degrees steam is entirely cut off from the engine, 45 while by continuing the rotation until half a revolution is accomplished the engine will be reversed.

While I have described the exhaust-openings or ports in the rocking valves 13 as cut 50 into the transverse exhaust channels or openings 27 at their inner ends, it will readily be seen that by connecting the cylindrical valve 23 with the rocking valves 13, I am able to simplify this construction by merely cutting all four of the ports in said valve 13 directly through the body of the valve 13. The 55 Z-shaped exhaust-channels 26 in the cylindrical valve form the connections between the exhaust-ports and the exhaust-openings 16 lying between the said ports.

The valve-stems 14 are so connected with the pistons that the reciprocation of the latter produces an oscillation of the valves. At 60 each oscillation of each valve the live-steam ports 21 register one with one of the live-

steam ports 25 of the valve 23, and at the same time one of the ports 17 on the opposite part of the valve 13 registers with one of the exhaust-channels 26, which communicates with the other end of the cylinder, to which 70 steam is flowing through the port 25. As the valve oscillates in the opposite direction, the port 22 upon the opposite side of the center of the valve registers with the live-steam port 25^a, while the port 21 registers with the other 75 end of the exhaust-channel 26. This operation is duplicated in each of the cylindrical valves at every stroke of the piston. The cut-off, by turning the valve 23 through one-half of a revolution, is so fully shown in Fig. 80 3 as to require no explanation, and the reversal of the engine by a revolution of said valve through an arc of ninety degrees will readily be understood by comparing the relative positions of the live-steam and exhaust 85 ports in Figs. 4 and 5, respectively.

What I claim is—

1. In a steam-engine having oscillating cylindrical valves provided with alternating live-steam and exhaust ports, a cylindrical reversing-valve arranged within the oscillating valves and having alternating live-steam ports cut entirely through the cylindrical body, said reversing-valve also provided with exhaust-channels cut into opposite faces and 90 alternating with the live-steam ports, said alternating channels communicating with a central transverse channel, substantially as described.

2. In a steam-engine having an oscillating hollow cylindrical valve or valves provided with alternating live-steam and exhaust ports, a cylindrical reversing-valve lying within the said valve or valves and having journals bearing in the walls of the steam-chest, said reversing-valve having live-steam ports cut 100 through its body on opposite sides of the cylindrical axis and on opposite sides of one or more transverse lines coinciding with the exhaust-openings of the valve-seat, and being 105 also provided with transverse channels on opposite sides of the cylindrical body cut in said transverse lines and communicating with exhaust-channels alternating with the steam-ports, substantially as described.

3. In a steam-engine having a concave valve-seat provided with a line of ports and exhaust-openings cut transversely between said ports, an oscillating hollow cylindrical valve or valves having live-steam ports and 115 exhaust-ports arranged alternately on opposite sides of exhaust-openings cut transversely in line with those in the valve-seat, a cylindrical reversing-valve having journal-bearings in the valve-chest, one of said journals 120 prolonged to extend through a stuffing-box, said valve having live-steam ports cut through its body on opposite sides of its axis, and transverse channels registering with the exhaust-openings in the oscillating valve and pro- 125 130

vided with exhaust-channels alternating with the live-steam ports and communicating with the transverse channels, and lever being mounted on the projecting journal of the reversing-valve, and the front of the oscillating valves being cut away to form a steam-chamber and provided with ports, substantially as described.

In testimony whereof I have affixed my signature in presence of two witnesses.

EDWARD G. SHORTT.
